UNITED STATES PATENT OFFICE.

ALBERT CHAMPION, OF FLINT, MICHIGAN, ASSIGNOR TO A C SPARK PLUG COMPANY,
OF FLINT, MICHIGAN, A COMPANY OF MICHIGAN.

INSTRUMENT PANEL.

Application filed July 2, 1926. Serial No. 120,240.

This invention relates to instrument panels and particularly to those of the type in which the instruments are indirectly illuminated. In the present instance indirect illumination is provided by locating the light source at the rear of the panel and spacing the instruments from the rear of the panel so as to permit some of the rays from the source to strike the faces of the instruments. 5 One feature of my invention consists in the provision of a simple spacing means to hold the instrument in proper position with respect to the light source and preferably in a slightly tilted position so as to secure more effective illumination. This spacing means in its simple form consists of an arcuate ring snapped over the instrument bezel and cut away on the side adjacent the light source to permit passage of rays of light to the 10 dial.

Another feature of my invention consists in providing in the usual instrument face plate in addition to the display apertures for the dials, an aperture for the passage of light to certain of the dials at the rear of the face plate, thus eliminating shadows which would otherwise be cast. This additional aperture is preferably in the form of a slit in the face plate directly above one of the display 15 apertures and preferably so shaped that the interior of the instrument is not visible through the slit from the ordinary reading position.

Referring to the drawings:

Figure 1 is a front elevation of an instrument panel embodying my invention. 35

Figure 2 is a rear elevation thereof.

Figure 3 is a section on line 3-3 of Figure 2, parts being shown in elevation for 40 simplicity.

Figure 4 is a perspective view of the spacer element.

The reference character 2 indicates the usual instrument board provided upon automobiles. The reference character 4 indicates a removable instrument panel upon which, for convenience, the instruments are mounted prior to the fitting of the panel in the opening 6 in the instrument board. Obviously, if desired the panel 4 may be formed integrally with the instrument board. I have indicated three instruments mounted on the panel. The instruments numbered 8 and 10 are shown as bolted directly to the 45 panel, each of the instrument casings being provided with openings 11 covered with transparent material and facing the light source which is preferably in the form of a bulb 12 removably secured to the rear of the panel by spring clips 14. The instrument casings 8 and 10 are so arranged that the light passing through the apertures 11 falls upon the instrument dials, portions of which are displayed through arcuate openings 13 provided in the panel. 16 indicates an instrument, in this case a speedometer, in the mounting and in the construction of the face plate of which the novel features constituting my invention are employed. If desired, these features may likewise be utilized 50 in connection with the instrument shown at 8 and 10 but for simplicity I have restricted the showing to the speedometer 16. The speedometer 16 is of conventional construction except for the face plate. The mechanism of the speedometer is enclosed in a casing 20 provided with a face plate 22 having openings 24 through which the instrument dials are visible. The instrument panel is likewise provided with an opening 26 for 55 the display of these dials. The edge of the opening is inturned as indicated at 44. The face plate is covered by a transparent plate 28 secured to the casing by means of bezel 30. Between the instrument 16 and the rear of the panel is arranged a spacing element 32 shown in detail in Figure 4. This spacer element is arcuate in shape as shown and is provided with a flange 34 adapted to snap over the projecting portion of the bezel 30 or, 60 if preferred, over a similar projection formed upon the casing 20. The spacer is also provided with a flange 46 snugly fitting the inturned edge 44 of the opening 26 to insure proper positioning of the instrument 65 and spacer at the opening. The spacer is discontinuous to provide a gap indicated at 36 at the side adjacent the light source 12 to permit some of the rays from the light source to fall upon the instrument dials at the rear of the panel. The spacer is also preferably of tapered form, the largest portion 40 being the portion nearest the light source so that the instrument is held in an inclined position 70 which permits the passage of a greater quantity of light to the face of the instrument. The instrument and the spacer 32 may be secured to the panel by any suitable means such as clamping devices 42.

With the construction so far described, the 75

100

105

110

- portion of the face plate between the adjacent openings 24 would cast shadows upon the lower dials. To avoid this the material of the face plate between the upper openings is 5 provided with an opening 48 produced by slitting the material of the face plate and pressing it rearwardly. The opening thus formed permits the passage of light to the dials at the rear of the face plate eliminating shadows, but at the same time the face plate presents a substantially unbroken appearance when viewed from the usual reading position.
- I claim:
- 15 1. The combination of an automobile instrument panel, an instrument mounted on the panel, a face plate for the instrument, said face plate having an aperture for the display of the dial, a light source arranged 20 at one side of the instrument, said face plate being formed with an aperture adjacent the first named aperture and facing the light source for the projection of light upon the dial, said second named aperture being 25 formed by slitting the face plate and pressing the material at one side of the slit toward the rear of the instrument so as to render the aperture substantially invisible when viewed from ordinary reading position.
  - 30 2. A panel, an instrument on the panel, a source of light, spacing means between the instrument and the panel, such spacing means having an aperture for the projection of light from the source upon said instrument, said instrument being provided with a face plate having an aperture for the inspection of the dial, said face plate being provided with a second aperture facing the light source for the projection of light upon the 35 dial at the rear of the face plate.
  - 40 3. An instrument having a casing, a cover for the casing including a face plate having a dial inspection aperture, said face plate being provided with a second aperture facing in a different direction from said inspection aperture for the projection of light upon the dial at the rear of the face plate.
  - 45 4. A stamped face plate for an instrument having an aperture for the display of the dial and an inwardly pressed lip adjacent the aperture for the projection of the light upon the dial at the rear of the aperture.
  - 50 5. The combination of an instrument panel, an instrument mounted on the panel and provided with an outwardly projecting bezel portion, and a spacing member between the instrument and the panel and provided

with a flange fitting the bezel portion, said flange being of tapered cross section and provided with a cut away portion to permit projection of light upon the instrument. 60

6. The combination of an instrument panel having an opening therein, an instrument arranged for display at the opening, detachable spacing means interposed between the instrument and the rear of the panel and arranged to tilt the instrument away from the panel, means for clamping the instrument and the spacing means to the rear of 70 the panel, a source of light at the rear of the panel and lying between the plane of the instrument panel and the plane of the instrument face, said spacing means being cut away adjacent the light source to permit the 75 light to illuminate the face of the instrument.

7. The combination of an instrument panel having an opening therein, an instrument mounted on the panel for display at the opening, a source of light at the rear of the panel for illuminating the face of the instrument, spacing means interposed between the instrument and the rear of the panel and arranged to space the portion of the instrument adjacent the light source a greater distance from the panel than the portion remote from the light source, said means being discontinuous at the side adjacent the light source to permit projection of light upon 90 the face of the instrument, said spacing means comprising a resilient wedge shaped arcuate member snapped over a portion of the instrument casing. 85

8. The combination of an instrument panel having an opening therein, an instrument mounted on the panel for display at the opening, a source of light at the rear of the panel for illuminating the face of the instrument, spacing means interposed between 100 the instrument and the rear of the panel and arranged to space the portion of the instrument adjacent the light source a greater distance from the panel than the portion remote from the light source, said means being discontinuous at the side adjacent the light source to permit projection of light upon 105 the face of the instrument, the edge around said opening being inturned and said spacing means comprising an arcuate member 110 snugly engaging the said inturned edge and having detachable engagement with the instrument casing.

In testimony whereof I affix my signature.

A. CHAMPION.
